(No Model.)

T. BUTLER.

FLUSHING PIPE FOR WATER CLOSETS.

No. 376,137.

Patented Jan. 10, 1888.

UNITED STATES PATENT OFFICE.

THEODORE BUTLER, OF NEW YORK, N. Y., ASSIGNOR TO THE J. L. MOTT IRON WORKS, OF SAME PLACE.

FLUSHING-PIPE FOR WATER-CLOSETS.

SPECIFICATION forming part of Letters Patent No. 376,137, dated January 10, 1888.

Application filed March 7, 1887. Serial No. 229,973. (No model.)

To all whom it may concern:

Be it known that I, THEODORE BUTLER, of the city, county, and State of New York, have invented an Improvement in Flushing-Pipes for Water-Closets, of which the following is a specification.

In first-class plumbing work the water-closet is very frequently not incased with wood-work and the flushing-pipe is of polished brass and 10 extends from the water-closet up to the cistern. In this class of work difficulty is experienced in placing the closet in position in relation to the wall and to the cistern with sufficient accuracy to make use of the rigid and non-adjustable 15 couplings and bends heretofore employed for connecting the ends of the flushing-pipe to the closet and cistern, respectively; hence the cistern and closet have heretofore generally been fitted to place, and then special 20 connections have been made for the respective ends of the brass pipe after the pipe has been bent while hot at the top and bottom ends, and this has necessitated delay in sending to the shop or manufactory and increased the expense. 25

My present improvements are made with reference to adjusting the connections at the ends of the brass flushing-pipe, so as to allow for the ordinary variations in the setting of the 30 closet and cistern.

I make use of a compound curved coupling-pipe screwed upon the upper end of the vertical brass pipe and extending to the screw-socket upon the under side of the cistern, so 35 that the upper end of the straight brass pipe can be moved laterally to a slight extent to bring it vertical, and the elbow at the lower end of the vertical brass pipe is provided with a socket and elastic packing and clamping ring 40 to allow for adjustment and for making a tight joint, and a screw-coupling between the closet and the elbow allows for adapting the pipe to the distance between the closet and the wall.

In the drawings, Figure 1 shows the two ends 45 of the flushing-pipe by vertical sections; and Fig. 2 is a perspective view of the closet, cistern, and flushing-pipe.

The rim A of the water-closet is adapted to receive the plate B at the horn or tubular con-

nection, and there is a screw-thread around 50 the thimble B' of this plate to receive the coupling-ring c, that clamps the flanged end of the nipple D to the ring e of leather or rubber. This nipple D is screw-threaded upon the outside, and is screwed into one end of the elbow 55 F, and the socket of this elbow is sufficiently long to allow for the nipple D to be screwed in more or less to suit the distance between the wall H and the closet, and this nipple is usually long enough to allow for being sawed or 60 filed off if too long.

There is a clamp-ring, K, around this nipple D, so that a water-tight joint will be made by red lead or similar material between the end of the elbow F and the ring K and around the 65 screw.

At the upper end of the elbow F is a tubular socket adapted to receive within it the brass or other polished flushing-pipe M and the coupling-ring N, screwed upon the outside of the elbow F at its upper end, and the inclosed washer O, of india-rubber or similar material, and with a brass ring, forms a tight joint against the smooth exterior surface of the pipe M after it has been raised or lowered to 75 suit the position of the closet-cistern.

The upper end of the vertical flushing-pipe M is screwed into the lower end of the compound curved coupling-pipe P, and at the upper end there is a flange and coupling-ring, Q, 80 by means of which the flushing-pipe is connected at its upper end with the screw-socket R, that passes into the cistern S, as usual.

Ordinarily, the socket R is at some distance from the wall; hence it is necessary to make 85 the coupling-pipe P as a compound curve to pass at its lower end back to the wall, and this lower end may be moved laterally at the wall, so as to bring the flushing-pipe M correctly into position, so that the same may be accurately vertical.

I am aware that it is common to bend the lead flushing-pipe with a compound curve below the cistern; also, that devices for adjusting the lengths of tubular connections have 95 been applied to basins, and screw-couplings have been applied to the porcelain tube upon water-closets. In my improvement I am able

to connect up the brass flushing-pipe and to allow for all ordinary differences in placing the closet and cistern without requiring any special changes or fittings, as heretofore indis-
5 pensable.

I claim as my invention—

1. The combination, with the vertical flushing-pipe M and the compound curved coupling-pipe P, connecting the pipe M to the cistern, of the elbow F, having a socket at its upper end, into which the lower end of the pipe M enters, the coupling-ring N, and washer O, screw-nipple D, ring K, and thimble B', and coupling e, substantially as set forth.
- 15 2. The combination, with the water-closet and cistern, of a flushing-pipe, M, of brass or

similar material, adapted to be cut off of the required length and having a smooth exterior surface, the nipple D, connected with the water-closet, the elbow F, screwed to the nipple 20 D and having a socket at its upper end for the reception of the lower end of the pipe M, and a screw-ring, N, and elastic packing for making a tight joint at the upper end of the elbow F, substantially as specified.

Signed by me this 3d day of March, A. D. 25
1887.

THEODORE BUTLER.
